(57) **CLAIM**

The ornamental design for a flash trigger transmitter, as shown and described.

DESCRIPTION

FIG. 1 is a front view of a flash trigger transmitter wherein a connector of the flash trigger transmitter is shown in a straight configuration;

FIG. 2 is a rear view of the flash trigger transmitter of FIG. 1; FIG. 3 is a left view of the flash trigger transmitter of FIG. 1; FIG. 4 is a right view of the flash trigger transmitter of FIG. 1; FIG. 5 is a top view of the flash trigger transmitter of FIG. 1; FIG. 6 is a bottom view of the flash trigger transmitter of FIG. 1;

FIG. 7 is a front view of the flash trigger transmitter of FIG. 1 wherein the connector is shown in a pivoted configuration; FIG. 8 is a rear view of the flash trigger transmitter of FIG. 7; FIG. 9 is a left view of the flash trigger transmitter of FIG. 7; FIG. 10 is a right view of the flash trigger transmitter of FIG. 7;

FIG. 11 is a top view of the flash trigger transmitter of FIG. 7; and,

FIG. 12 is a bottom view of the flash trigger transmitter of FIG. 7.

The broken line showing of the flash trigger transmitter forms no part of the claimed design.
